(57) **CLAIM**

(21) Appl. No.: **29/165,896**

The ornamental design for a depth limiting footing for a
hollow frame ladder, as shown and described.

(22) Filed: **Aug. 20, 2002**

DESCRIPTION

(51) LOC (7) Cl. **25-04**
(52) U.S. Cl. **D25/68**
(58) Field of Search D25/68, 69; 182/107,
182/108, 109

FIG. 1 is a top and front perspective view of a depth limiting
footing for a hollow frame ladder showing our new design;
FIG. 2 is a front view thereof;
FIG. 3 is a side view thereof, the unshown opposite side
being of identical appearance;
FIG. 4 is a top view thereof; and,
FIG. 5 is a perspective view of the depth limiting footing for
a hollow frame ladder in operative engagement, the broken
lines showing the ladder and one depth limiting footing is for
illustrative purposes only and form no part of the claimed
design.
